UNITED STATES PATENT OFFICE.

VIRGIL P. WENDLE AND MARTIN L. HUNKER, OF DOVER, OHIO, ASSIGNORS TO THE REEVES MANUFACTURING COMPANY, OF DOVER, OHIO, A CORPORATION OF OHIO.

SHEET-METAL RECEPTACLE.

Application filed March 15, 1926. Serial No. 94,772.

The invention relates to sheet metal receptacles, especially adapted for containing nails and other hardware and the like, and more particularly to collapsible receptacles which may be easily and readily assembled or knocked down and which will occupy a minimum amount of space in collapsed condition.

The object of the improvement is to provide a collapsible sheet metal receptacle, the adjoining edge portions of the different parts of the receptacle being corrugated and provided with spaced apertures through which a wire or rod is passed to hold the parts together.

An embodiment of the invention is illustrated in the accompanying drawings, in which—

Figure 1 is a perspective view of a barrel or keg constructed in accordance with the invention, parts being broken away for the purpose of illustration;

Fig. 2, a detached perspective view of one-half of the barrel or keg showing a portion of one head connected thereto;

Fig. 3, a detached perspective view of one of the heads, a portion being broken away to show the cross sectional shape;

Fig. 4, a transverse sectional view through the barrel or keg;

Fig. 5, a fragmentary perspective view of a portion of the barrel or keg showing a modified form of head;

Fig. 6, a perspective view of a rectangular box formed in accordance with the invention;

Fig. 7, a detached perspective view of one side, and one end, member of the box, and

Fig. 8, a perspective view of a box, embodying the invention, adapted for containing tin sheets or the like.

Similar numerals of reference indicate corresponding parts throughout the drawings.

Referring first to Figures 1 to 5 inclusive, a cylindrical receptacle, such as a barrel, keg or the like, is illustrated. This receptacle is formed of two similar, half-round sections 1, the longitudinal edges of which may be corrugated, as shown at 2, in Figure 1, or these corrugations may extend transversely entirely around each section, as shown at 2^a, in Figure 2.

For the purpose of strengthening the struc-

ture, shown in Figure 1, each section may be provided, at spaced intervals, with transverse corrugations 3. The opposite ends of each of the half sections are provided with longitudinally disposed corrugations 4, the transverse corrugations, 2 or 2^a, terminating a short distance from each end of the receptacle.

The heads 5, shown in Figures 1 to 3 inclusive, are arranged to extend into the end portions of the receptacle, each head being provided with the outwardly inclined angular flange 6 terminating in an inwardly disposed peripheral flange 7, corrugated, similar to the end corrugations 4 of the receptacle, and adapted to be received over the same, as shown in Figures 1 and 2.

The corrugated edges 2 or 2^a, of the half sections, are provided with spaced apertures 8 through which a wire or rod 9 may be passed, for detachably securing the two half sections together, to form a cylindrical receptacle as shown in Figures 1 and 4.

Similar apertures 10 are provided in the corrugated ends 4 and corrugated flanges 7 of the heads, the wire 11 being passed through the same to detachably secure the heads upon the receptacle, as shown in Figures 1 and 2. If desired, the heads may be formed as shown at 5^a in Figure 5, being adapted to be inserted within the ends of the receptacle, each head having a peripheral, outturned, corrugated flange 7^a to fit within the corrugated end portions 4 of the receptacle and to be connected thereto, as by the wire 11, in the manner above described.

When it is desired to collapse or knock down the receptacle, for the purpose of shipping, it is obvious that considerably less space will be occupied by the knocked down parts than is possible with the ordinary non-collapsible receptacle of this character. The wires 9 and 11 are withdrawn and the heads may be piled compactly in a small space while the half sections of the body portion may be nested together thus permitting the packing of a great many receptacles within a very small space.

As shown in Figures 6 to 8 inclusive the invention is applicable to rectangular receptacles as well as barrels, kegs and other cylindrical receptacles.

The collapsible box, shown in Figures 6

and 7, is made up of the side members 12, end members 13 and top and bottom members 14 of similar construction.

Each of the side members 12, and end members 13, may be provided with any suitable corrugations, as shown at 15 for the purpose of reinforcing the same. One end of each side and end member is provided with longitudinal corrugations 16, the other end thereof having an angular, corrugated flange 17 arranged to overlap the adjoining end 16 of the adjacent member, apertures 18 being provided for the reception of a wire or rod 19 by which the side and end members are detachably secured together.

Each of the top and bottom members is provided with an angular transversely corrugated flange 20 adapted to overlap the adjacent, similarly corrugated upper and lower edges 21, of the side and end members, and apertures 22 are formed in these edges and flanges to receive the wires 23 by means of which the top and bottom members are secured to the body portion of the receptacle.

In Figure 8 is illustrated a box especially adaptable for containing tin sheets, or the like, which includes the receptacle 25 and cover 26. The side and end walls of the receptacle are corrugated vertically, as shown at 27, and the cover is provided with a depending, similarly corrugated flange 28 adapted to fit over the receptacle, apertures 29 being provided in the corrugated portions of the receptacle and cover to receive the wires 30 for securing the cover upon the receptacle.

In order to hold the wires, in all of the forms of the invention, against accidental removal, the end portions of the wires may be bent or twisted back or outward at an angle, as illustrated in the several views, in order to temporarily retain the same in place and thus hold the parts of the receptacles together.

We claim:

1. A receptacle formed of a plurality of sheet metal members having overlapping, uniformly corrugated edge portions provided with spaced apertures, the apertures in the respective overlapping portions being so aligned that a wire may be inserted through the apertures without distortion of the wire, and straight wires located through said apertures for attaching said members together.

2. A receptacle formed of a plurality of sheet metal members having overlapping, uniformly corrugated edge portions provided with spaced apertures, wires located through said apertures for attaching the members together, the end edge portion of the receptacle being corrugated, and provided with spaced apertures, a cover having a corrugated flange overlapping said end edge portion and provided with spaced ap-

tures, and a wire located through the apertures in the end edge portion and cover, for attaching the cover.

3. A receptacle having uniformly corrugated edge portions, provided with spaced apertures, a cover having a corrugated flange adapted to overlap said corrugated edge portions and provided with spaced apertures and a wire located through all of said apertures for attaching the cover to the receptacle.

4. A receptacle comprising side walls having uniformly corrugated upper and lower edge portions provided with spaced apertures, a cover having a corrugated flange adapted to overlap said corrugated upper edge portions and provided with spaced apertures, a bottom having a corrugated flange adapted to overlap said corrugated lower edge portions and provided with spaced apertures, the apertures in the respective overlapping portions being so aligned that a wire may be inserted through the apertures without distortion of the wire, and wires located through said apertures for attaching said cover and bottom to the side walls.

5. A receptacle of a plurality of sheet metal side members having overlapping, uniformly corrugated side edge portions provided with spaced apertures, the apertures in the respective overlapping portions being so aligned that a wire may be inserted through the apertures without distortion of the wire, a wire located through said apertures for attaching the side members together, the lower edge portions of the side members being uniformly corrugated, and provided with spaced apertures, a bottom member having a corrugated flange adapted to overlap the corrugated lower edge portions of the side members and provided with spaced apertures, the apertures in the lower edge portions and in the bottom member being so aligned that a wire may be inserted through the apertures without distortion of the wire, and a wire located through the apertures of the bottom flange and lower edge portions of the side members, for attaching the bottom to the receptacle.

6. A receptacle having uniformly corrugated edge portions provided with spaced apertures, a bottom having a corrugated flange adapted to overlap said corrugated edge portions and provided with spaced apertures, the apertures in the lower edge portions and in the bottom member being so aligned that a wire may be inserted through the apertures without distortion of the wire, and a wire located through all of said apertures for attaching said bottom to the receptacle.

In testimony that we claim the above, we have hereunto subscribed our names.

VIRGIL P. WENDLE.
MARTIN L. HUNKER.
